DEVICE TO EASE CHILDBIRTH

Mark Hornstein, New York, N. Y.

Application February 2, 1937, Serial No. 123,587

4 Claims. (Cl. 128—361)

This invention relates to methods and devices for easing childbirth.

Childbirth seldom meets with serious difficulties where the opening of the womb has proceeded to the ideal culmination. The ideal, however, is not attained merely by a degree of dilatation which may be said arbitrarily to allow passage of the head. The ideal degree of opening is more than a spreading of the orifice of the organ. Authorities recognize that it consists of a pulling up of the lower passive portion of the womb into the upper active uterine musculature as a result of the muscular action of the latter. The resultant spreading of the orifice is a necessary incident resulting from pull exerted upon every point of the orificial ring. So that it may be truly said that the womb opening is pulled up past the head rather than the head passing through the opening.

Three indispensable consequences of the above are:

1. The child can emerge from the womb.
2. The tight bony pelvis is cleared of womb and is entirely available for descent and passage of the head.
3. The shortened womb is thicker and stronger for the ensuing expulsion of the child from the pelvis.

The numerous instances of difficulty in childbirth are usually associated with imperfection in this evolution of the lower portion of the womb and the obstetrician is frequently compelled after days of waiting to resort to the use of instruments before the completion of this so-called first stage of labor. Not only is the child pulled through an insufficiently open womb with resultant tearing of the neck of this organ, but the pulling is also done through a tight bony pelvis into which the muscular tube constituting the lower end of the womb is telescoped. The head is therefore being forced through a virtually smaller pelvis. Not uncommonly, this causes excessive compression of the soft head, injuries to the brain, and death of the child. Before the long, tedious labor has finally been ended the woman has undergone days of suffering and exhaustion and may become easy prey to infection to which the long labor has exposed her.

In search for the cause of this arrest or delay in the evolution during labor of the lower portion of the womb, irrespective of any other concomitant aberration from the accepted normal, it has seemed to the author that the chief hindrance rests in the pressure of the head against the sides of the lower portion of the womb. That

the head acts as a drag upon this portion, delaying its upward excursion and causing, moreover, the uterine contractions to be more painful than necessary. The fact that early breaking of the water bag often goes hand in hand with delayed labor is only one corroborative factor. The usual positions assumed by the expectant mother during labor seemed to be the main cause.

Experimenting with the woman in the knee-elbow and in the knee shoulder position did bring about startling results in promoting progress in labor. These positions, however, are not easy to maintain for a sufficient time as they cause some degree of exhaustion and are dependent upon the willingness of the patient to cooperate. As the patient must be kept wide-awake it is not feasible to administer drugs for the relief of pain and although in the normal case the benefits of the posture are so rapid that exhaustion does not take place and even relief from drugs can be dispensed with, in the more difficult case a longer maintenance of the posture is not practicable, much as this is necessary.

The appliance has therefore been devised to overcome these shortcomings. By the use of this, the patient is kept comfortable and relaxed. Drugs may be given and the posture may be maintained for many hours without due objections by the patient.

The posture recommended is that which will favor upward recession of the womb and its contents. As these are brought out of the true narrow pelvic cavity the lower portion of the womb is no longer hindered in its upward excursion by pressure of the head against it and in turn against the walls of the true pelvis. The contractions of the womb immediately become orderly, rhythmic and strong, at the same time distinctly less painful. The opening and upward excursion of the lower portion proceeds apace and the results are frequently astonishing, nearly always substantial.

While the results achieved by the method are self-evident the explanations for their occurrence are at variance with established teaching. The general view is that the head must be "engaged" in the true pelvis even before the onset of labor. This assumes the requisite existence of a pelvis which is large enough to accommodate not only head but head clothed with a thick muscular coat, the lower uterine portion. Closer observation shows that where these conditions are met natural processes bring about upward displacement of the head as soon as labor starts provided

that there is a sufficient amount of amniotic fluid forced down below the head by the pressure exerted from above by the contractions of the uterine musculature, thus floating the head back and 5 prompting a progressive labor. Where this condition is not met, either on account of scanty fluid, early breaking of the "water bag", or other mechanical conditions labor is retarded.

Summing up the main advantages of the new 10 method and the device through which it operates, they are: Shortening of the normal and retarded labor, shortening the time required to prepare the abnormal case for corrective treatment, diminution in the incidence of intracranial 15 injuries to the child, practical elimination of lacerations of the neck of the womb and the sequelae of this injury, less cause for operating and instrumental delivery.

Aside of a novel posture and method of easing 20 childbirth, my invention also relates to a device for aiding the expectant mother to keep in this desirable position in a pleasing, non-tiring and efficient manner.

In the drawing forming a part of this specification 25 and accompanying the same:

Fig. 1 is a perspective view of my device to be used for aiding and easing childbirth;

Fig. 2 is a side elevation thereof, portions of 30 the same having been broken away;

Fig. 3 is a front elevation, portions of the device having been removed;

Fig. 4 is a fragmentary detail showing the 35 shape and arrangement of a central opening in my invention, and

Fig. 5 is another fragmentary sectional detail showing the method for removably securing a 40 textile body on the frames of my devices, while

Fig. 6 is a diagram showing the application 45 of my device and said favorable position of an expectant mother.

Referring now to the diagram of Fig. 6 showing 50 the basic idea of my invention and the application of one form of my device, the expectant mother is generally indicated by the numeral 10 and she is kept in a downwardly turned position, the head possibly resting on the pillows 11.

My device is generally indicated by the numeral 55 14 and is in the form of a transverse arch placed underneath the center of the body and may be used for the main support thereof permitting the rest of the body to change its position, to move about for momentary rest and relaxation if the expectant mother so desires, the device 14 being placed on the bed 12, 13, as shown.

An opening 15 may be provided in the arch 14 and the center part 16 of the underside of the body of the expectant mother may freely depend 60 therefrom, thereby aiding, or making possible, the favorable conditions as to the pelvic opening, the womb, and the head of the fetus, explained hereinbefore.

Referring now more closely to the embodiment 65 of my device to be used in connection with this novel method of aiding childbirth, said device, as has been mentioned hereinbefore, is generally an arch shaped body 14, in the embodiment shown having two arcuate longitudinal or side frames 17 and 18 kept at a desired distance by two 70 transverse pipe members 19 and 20 arranged between the respective lower ends of the two arcs 17 and 18. A tie rod 21 may pass through each transverse pipe 19 and 20 having a head 22 at one end and a wing nut 23 at the other whereby 75 the ends of the arcs 17 and 18 may be tightly

clamped on said transverse pipes 19 and 20, as will be understood.

A textile sheet material 24, preferably a canvas sheet is stretched out between the frame members 17, 18, 19 and 20 forming an arc proper 25 5 of slightly and resiliently yielding character. The marginal edge portions of said canvas are formed with tubular loops 26 encircling the arcuate and transverse frame members 17, 18, 19 and 20. 10

My device when assembled will cause the canvas member 24 to be comparatively tightly stretched between the said frame members forming the arch shaped body shown in Fig. 1.

In the top center portion of my device I also 15 arrange an opening 27, preferably of oval shape, the longer axis of the oval being in parallelism with the planes of the arcs 17 and 18 and said opening preferably also showing incisions 28 at its four centers for the purpose described hereinbefore, which incisions, however, may be omitted.

It will be understood that the edges of the opening 27 may be lined or otherwise made more 25 comfortable to bear, and that the rear end of my device, in the diagrams generally indicated by the numeral 29, will be somewhat raised, as for instance making the rearward end of the arcs 17 and 18 indicated by the numeral 30 somewhat longer than the forward ends 31 thereof. 30

My device may be disassembled in an easy and quick manner when so desired, as for instance when transporting the same from one place to another, and may be set up again in a similarly easy and quick manner. For this purpose the 35 wing nuts 23 will first be removed, then the tie rods 21 will be pulled out of the transverse pipe members 19 and 20, whereupon the canvas body 24 may be pulled off the arc frames 17 and 18 together with the pipe members 19 and 20, and the 40 device again set up with the same ease in a reverse manner, when it is desired to use it.

As has been pointed out, it is desirable to place the parturient woman in the knee-elbow position. But as this position may have the effect of producing fatigue and offers other obstacles, I invented this appliance which overcomes such objections. This appliance aims to produce the same effects as the knee-elbow position, to wit: to keep the trunk of the body in a generally horizontal position and to allow the abdomen and its contents to remain suspended vertically from the trunk. While so suspended, the womb and its contents, principally the child, owing to their own weight are lifted out of the pelvic cavity, thus allowing the lower pole of the womb including the opening free play, and thus promoting, easing and accelerating the opening of the womb. 55

The manner in which the appliance accomplishes these objects consists of applying support 60 chiefly in two areas: The bony pelvic girdle, at the lower end, and the bony region of the breastbone and adjoining ribs, at the other. Some support is also applied to the soft flanks by means of the sides of the central opening. The abdomen 65 remains freely suspended through the opening. It is also essential that the suspended abdomen remain freely exposed and accessible to the physician's hands for purposes of palpation as this is his chief means of ascertaining the degree of 70 progress of the labor.

While the "knee-elbow" position and the arch-shaped support, described hereinbefore, are preferred in my novel treatment and device to ease childbirth, beneficial results may also be at- 75

tained if the expectant mother is simply kept in a resting position face downward, a support being provided for the parts of the body around the abdomen, as has been pointed out hereinbefore, 5 while the abdomen is permitted to freely depend through an opening into a space within said support, a further opening or openings at the side or at the bottom of the device being provided to give easy, direct and unobstructed access to 10 the abdomen for the described operations, observations and manipulations of the attending physician.

While I have described a preferred embodiment of the device, it is to be understood that 15 changes and variations may be made in the details of construction thereof, and I desire to reserve my rights to all such changes and variations which are within the spirit of this specification and the scope of the claims hereunto appended.

20 What I claim as new, is:

1. A support for the underside of the middle portion of the body of an expectant mother, before childbirth, comprising an arch shaped body adapted to be placed transversely underneath said portion of the body of the expectant mother, an opening being provided in said arch permitting the abdomen to freely depend therethrough, said arch shaped body having two longitudinal arcuate end frame portions, and a sheet 25 material secured on said frames and stretched between them.

2. A support for the underside of the middle portion of the body of an expectant mother, before childbirth, comprising an arch shaped body 30 adapted to be placed transversely underneath said portion of the body of the expectant mother, an opening being provided in said arch permitting the abdomen to freely depend therethrough,

said arch shaped body having two longitudinal arcuate end frame portions, a sheet material secured on said frames and stretched between them, and two transverse members extending between the respective ends of said arc frames. 5

3. A support for the underside of the middle portion of the body of an expectant mother, before childbirth, comprising an arch shaped body adapted to be placed transversely underneath said portion of the body of the expectant mother, an opening being provided in said arch permitting the abdomen to freely depend therethrough, said arch shaped body having two longitudinal arcuate end frame portions, a sheet material secured on said frames and stretched between them, two transverse members extending between the respective ends of said arc frames, and means to detachably secure the respective ends of the arcuate and longitudinal frame members to one another. 15

4. A support for the underside of the middle portion of the body of an expectant mother, before childbirth, comprising an arch shaped body adapted to be placed transversely underneath said portion of the body of the expectant mother, an opening being provided in said arch permitting the abdomen to freely depend therethrough, said arch shaped body having two longitudinal arcuate end frame portions, a sheet material secured on said frames and stretched between them, two transverse members extending between the respective ends of said arc frames, means to detachably secure the respective ends of the arcuate and longitudinal frame members to one another, and means to remove said sheet and said transverse members from said arc members, or replace them thereon. 20 25 30 35

MARK HORNSTEIN.
